UNITED STATES PATENT OFFICE.

MICHAEL F. GLEESON, OF PALMER, MASSACHUSETTS, ASSIGNOR TO WRIGHT WIRE COMPANY, OF WORCESTER, MASSACHUSETTS, A CORPORATION OF MASSACHUSETTS.

FOUNDRY-RIDDLE.

1,147,858.

Specification of Letters Patent. Patented July 27, 1915.

Application filed January 24, 1914. Serial No. 814,107.

To all whom it may concern:

Be it known that I, MICHAEL F. GLEESON, a citizen of the United States, residing at Palmer, in the county of Hampden and Commonwealth of Massachusetts, have invented a new and useful Improvement in Foundry-Riddles, of which the following description, taken in connection with the accompanying drawings, is a specification.

10 The present invention relates to foundry riddles, or sieves, which are employed to riddle the sand used in the making of molds.

An object of the invention is to provide a durable and inexpensive device of the class 15 specified, which is capable of easy manufacture.

A further object consists in the production of a riddle in which the mesh is firmly and rigidly secured in the wall thereof by 20 means which grip the wires of the mesh, and are conformable to the interstices between said wires.

Other and further objects will appear in the description as hereinafter set forth and 25 in the claims appended thereto.

Referring to the drawings, Figure 1 is a side elevation of the riddle constituting the present invention; Fig. 2 is a fragmentary enlarged vertical sectional view thereof in 30 the plane of one of the strengthening wires, and Figs. 3, 4 and 5 are vertical sectional views through the wall and mesh at successive stages in the formation of the gripping means for the mesh.

35 Like reference characters are used to designate like parts in the different views.

In the drawings the cylindrical wall 1 of the riddle, which is preferably formed by welding or otherwise joining the ends of a 40 sheet of metal, has its upper edge turned outwardly into a bead 2, having a stiffening ring 3 therein, and is provided intermediate its upper and lower edges, about midway in the height of the riddle, with a circumferential stiffening corrugation 4. The 45 lower edge of the wall 1 is bent inwardly and upwardly as shown at 5 in Fig. 3, to form a channel 6 adapted to receive the downwardly bent edge 7 of a wire mesh disk 50 8 which forms the bottom of the riddle. The said edge 7 extends downwardly into the bottom of the channel 6, and is retained in this position when the portion 5 is bent to lie in a vertical plane, parallel with the 55 wall 1, as shown in Fig. 4. In this position

the space between the wall 1 and the portion 5 is entirely filled by the downwardly bent edge 7 of the disk 8. The final step in the formation of the retaining means for the disk 8 consists in compressing the edge 7 firmly between the wall 1 and portion 5 thereof, and, at the same time, forming a bead of peculiar character in both sides of the fold inclosing the edge 7, as shown in Fig. 5. Any convenient means may be employed for imparting the desired form to the bead. I prefer to employ a pair of rolls for the purpose, between which the folded edge is passed, so that the compression of the sides of the fold, and the shaping of the same, may be accomplished simultaneously. The outer or female roll is provided with a peripheral recess, adapted to impart a substantially semi-circular cross section to the bead 9 formed in the wall 1, while the inner or male roll is provided with a peripheral V-shaped projection, in opposition to the recess on the other roll, to impart a substantially V-shaped cross section to the bead 10 of the portion 5. As clearly shown in Figs. 80 2 and 5, the bead 10 crowds the adjacent portion of the disk edge 7 into the interior of the bead 9, whereby the disk 8 is stretched and held taut in its position within the riddle. Furthermore, sufficient pressure is exerted on the fold, in its passage between the rolls, to cause the sides thereof to conform substantially to the interstices between the wires of the edge 7 inclosed thereby, as clearly shown in Figs. 1, 2 and 5.

A plurality of supporting wires 11 are disposed diametrically of said riddle below the disk 8, their ends being passed through apertures formed in the flange 5 and wall 1, and preferably carried up above the corrugation 95 4, and through apertures 12 in the wall 1, each of said ends being secured by a downward bend 13. Rigidity is imparted to the wire by bending each end, as at 14, to conform to the corrugation 4. By means of 100 these wires 11 the disk 8 is prevented from stretching and sagging under the weight of the sand supported thereby.

I claim,

1. In a foundry riddle, a mesh disk having a depending edge, a cylindrical wall surrounding said disk and having a portion folded inwardly upon said wall to inclose said depending edge between it and said wall, with a projecting bead formed simul- 110

taneously in said wall, folded portion, and inclosed disk edge, near the free end of said folded portion, whereby the edge of said bead in said folded portion serves to draw 5 the mesh disk taut.

2. In a foundry riddle, a mesh disk, a cylindrical wall surrounding said disk and having a portion folded upon itself to inclose the edge of said disk, and a plurality 10 of supporting members for said disk, said

members passing through both sides of said fold below the plane of the disk, and attached to said wall above the plane of the disk.

Dated this sixteenth day of January 1914. 15

MICHAEL F. GLEESON.
